FREDERICK THOMAS BOWLER, OF HIGHLAND PARK, MICHIGAN

DOWEL

Application filed February 19, 1929. Serial No. 341,099.

This invention relates to a device designed and adapted to dowel or positively anchor one or more pieces of work to a fixture or base of divers machines or appurtenances, and is designed and adapted to supplant the ordinary solid dowel pin.

The prime object of the invention is the provision of a device of the indicated character, whereby certain benefits and advantages may be had, among which are the following, namely: to reduce manufacturing costs to the minimum by saving time and labor in carrying out doweling operations; to avoid scrapping of materials; to obviate excessive drilling; to be able to utilize the same device repeatedly; to facilitate the removal of the device for the purpose of separating pieces of work without requiring the removal of unwieldly parts or fixtures for effecting minor repairs, and also for interchanging fixtures and mechanical parts for various purposes whenever the occasion arises.

The nature of the invention and its distinguishing features and advantages will appear when the following specification is read in connection with the accompanying drawings, in which—

Figure 1 illustrates portions of two pieces of work and the expansible bushing of the device shown in perspective set in alined bores in said pieces.

Fig. 2 is a plan view of the parts shown in Fig. 1.

Fig. 3 is a view similar to Fig. 1, but showing the bushing expander or arbor and its spring inserted in the bushing, the expander or arbor being shown in a free position part way in the bushing.

Fig. 4 is a plan view of the parts shown in Fig. 2.

Fig. 5 is a vertical sectional view through the parts shown in Fig. 3, but showing the parts in locking relationship to effectively dowel or positively anchor the pieces of work together against relative movement.

Fig. 6 is a plan view illustrating more clearly the disposition of the bushing expander or arbor and the manner in which said bushing is expanded thereby in accordance with the showing in Fig. 5.

Fig. 7 is a view similar to Fig. 6, showing the bushing cap in place.

Fig. 8 is a sectional view taken on the line 8—8 of Fig. 7.

Fig. 9 is a sectional view taken on the line 55 9—9, of Fig. 7.

Fig. 10 is a perspective view of the bushing.

Fig. 11 is a perspective view of the bushing cap.

Fig. 12 illustrates an assemblage of the 60 parts of the device and the appurtenances for locking the device in operative position.

Fig. 13 is a view of the lower end of the wrench used for turning the bushing expander or arbor.

Fig. 14 is a perspective view of the bushing engaging element used for holding said bushing from turning while locking the device.

Fig. 15 is a plan view of one end of the 70 tool which cooperates with the element shown in Fig. 14 for holding said bushing.

Fig. 16 is a view illustrating the manner in which the bushing may be lifted out, or be withdrawn from association with the work 75 pieces.

Figs. 17 and 18 show modified forms of bushings, only portions of the bushings being shown.

As before stated the device of the present 80 invention is designed and adapted to be utilized for doweling for positively anchoring several pieces of work to fasten them together against relative movement, and said device also being readily detachable when it is desired to separate the pieces of work whenever the occasion arises for any purpose.

In the drawings there is shown two pieces of work 10 and 11, the former representing a base or fixture to which the piece 11 is fastened or anchored. The pieces 10 and 11 are provided with bores 12 and 13 respectively which are of the same diameter, so that when they are in alinement with each other will provide a recess having a smooth interior surface. The bore 12 has a conical bottom or end 14 which serves as a seat.

The device of the present invention which is intended to supplant the ordinary solid dowel pin, includes a cylindrical and tubular

element or bushing 15 having a ground finish, and to be made in all standard sizes. The bushing 15 will be made preferably of spring steel, or any other suitable metal having 5 springiness, and said bushing is split longitudinally as indicated at 16. The device also includes an expander or arbor 17 adapted to be inserted into the bushing and to be operated from the exterior of said bushing to expand 10 the bushing for the purpose of causing impingement of the latter against the walls of the bores in the pieces of work 10 and 11 when said bushing 15 is arranged in said bores. The expander or arbor 17 will be 15 made of metal, is quadrilateral in cross section, and has corners 18, either of which is adapted to be disposed in the split 16 in the bushing 15, when the expander or arbor 17 is placed in said bushing 16 as shown in Figs. 3 20 and 4; said expander or arbor 17 being of such cross sectional shape and size, as to accomplish this end. It is to be understood that the diameters of the bores 12 and 13 will be slightly larger than the diameter of the 25 bushing in order that the latter may be readily inserted into the same.

In order to set up a locking or clamping action of the bushing 15 to dowel or positively anchor the pieces of work together, 30 and also to release said bushing 15 for the purpose of separating the pieces of work, there is provided means presently to be described. One end of the bushing 15 has a notch or notches 19. As shown in Fig. 10, 35 the bushing 15 is provided with two notches 19 which are arranged diametrically opposite each other out of alignment with the bushing split to eliminate any possible weakness in or fracture of said bushing. If desired, the notches 19 may be arranged diagonally in line with the bushing split as shown in Fig. 17, or one notch may be arranged diametrically opposite the bushing split as shown in Fig. 18. One end of the expander 40 or arbor 17 has a transverse keyway or groove 20 therein, and the opposite end has a stud 21 to accommodate one end of a compression spring 22. Use is made of a short cylindrical and tubular element 23. The element 23 is 45 equal in diameter to the diameter of the bushing 15. The element 23 has a projection 24 at one end which is receivable in one of the notches 19 in the bushing 15. The element 23 also has projections 25 at the opposite end, 50 and said projections are arranged diametrically opposite each other. Use is made of a suitable tool 26 adapted to cooperate with the element 23 to hold the element against turning movement. The said tool 26 is therefore 55 provided with an annular member 27 at each end in the present instance adapted to fit around the element 23, and said member 27 has notches 28 which respectively receive 60 therein the projections 25 on the element 23. 65 It will now be understood that when the ele-

ment 23 is associated with the bushing 15, with the projection 24 on the element 23 disposed in one of the notches 19 in the bushing 15, and the tool 26 is applied to the element 23 with one of the members 27 surrounding the element 23 with the projections 25 disposed in the notches 28, the bushing 15 may be held against turning movement. Use is also made of a T-wrench 29 having a transverse key 30 adapted to be received in the keyway or groove 20 in the expander or arbor 17. The end of the wrench 29 having the key 30 is adapted to fit in the element 23, and has a collar 31 to limit the insertion of 70 said key end into said element 23.

It will now be understood that when the bushing 15 is placed in the aligned bores 12 and 13 in the pieces of work, and the expander or arbor 17 is inserted into the bushing 15 with one of the corners 18 disposed in the split 16, as shown most clearly in Figs. 3 and 4, the appurtenances 23, 26 and 29 may be used for the purpose of effectively expanding the bushing 15 to clamp or lock the same to securely dowel or positively anchor the 80 pieces of work together. It will be apparent that when the expander or arbor 17 is inserted into the bushing 15, the end of the expander or arbor 17 having the keyway or groove 20 will project beyond the related end of the bushing 15 having the notches 19, due to the fact that the spring 22 will be disposed between the seat 14 and the related end of the expander or arbor 17. The element 23 may then be associated with the bushing 15, the tool 26 may be applied to the bushing 23, and the wrench 29 may be engaged with the expander or arbor 17 in the manner explained hereinabove, whereupon the wrench 29 may be turned to impart similar movement 90 to the expander or arbor 17 substantially 120°, while the bushing 15 is held against turning movement. The corner 18 previously disposed in the split 16 together with the other corner 18 and contact surface 18' will 100 act on the inside of the bushing 15 to exert an equal amount of pressure in three directions. The bushing 15 is thus expanded in a locked position as shown most clearly in Figs. 5 and 6. The pieces of work 10 and 11 will 105 then be effectively doweled or positively anchored together.

It is to be understood that when locking the bushing 15, slight downward pressure is exerted on the expander or arbor 17 with the wrench 29 to compress the spring 22 and to bring the end of the expander or arbor 17 having the keyway 20 flush with the related end of the bushing 15. The friction set up by the three contact surfaces of the expander or arbor 17 on the inside of the bushing 16 prevents any possibility of the spring 22 moving the expander or arbor 17 from the locking position. When the expander or arbor 17 is in the locking position, its keyway 110

22 will be in alinement with the notches 19 in the bushing 15. It will therefore be apparent that use may be made of a cap 32 having a transverse key 33, the key to be received in the keyway 20 and notches 19, as shown most clearly in Figs. 8 and 9. The cap 32 will be held in place by friction, and will serve to prevent unintentional turning movement of the expander or arbor 17 when in the locked position.

To release the expander or arbor 17 and the bushing 15 the appurtenances 23, 26 and 29 are operated in the manner explained hereinabove to turn the expander or arbor 17 approximately 120° in either direction, thereby bringing one of the corners 18 of the expander into the bushing split 16. The expander 17 will then be in its free position, when both the expander 17 and the bushing 15 may be lifted out of the bores. The spring 22 will force the expander 17 longitudinally to a projected position with respect to the bushing 15 when the expander 17 is in the free position. The expander 17 may then be easily lifted out of the bushing 15. In order to facilitate the removal of the bushing 15, the end opposite that having the notches 19, has notches 34. A pair of spring tongs 35 having laterally projecting terminals 36 may be used for extracting the bushing 15, by engaging said terminals 36 respectively in said notches 34, as shown in Fig. 16.

It will be apparent that the device consists of the bushing 15, expander 17, spring 22 and seal or cap 32, the other parts herein described being used for the purpose of locking or releasing the parts which constitute the dowel.

It is to be understood that the expander or arbor 17 may be made of triangular stock, or of round stock having three flats machined thereon, providing two corners to be slightly surfaced while the remaining corner will have a considerably larger finishing surface, so that when the expander or arbor is inserted into the bushing, one corner will project into the split in the bushing approximately $\frac{1}{16}$ of an inch, to produce the desired camming action on the bushing when turned to its locking position. The expander or arbor 17 will have a three-point contact, and the frictional area of these contact surfaces on the inside of the bushing 15, will be less than the contact area of the outside surface of the bushing with the wall of the hole in the work, thereby reducing stress required for locking or releasing the parts.

The cap 32 is made of a piece of light gage sheet metal, so designed as to snap into the groove of the expander 17, and is large enough to cover the bushing to exclude cuttings or other foreign particles.

I claim:

1. A device for dowelling pieces of work comprising a cylindrical tubular dowel ele-

ment split at one point longitudinally and adapted to be inserted into and to be expanded and retained in position in alined bores in said pieces of work, an expander adapted to be inserted into said element, said expander having longitudinal contact portions, one of said portions being disposable in said split, when said expander is in free position in said element, and means on said expander adapted to receive a suitable tool to turn said expander to cause said portions to expand said element, for the aforesaid purpose.

2. A device for doweling pieces of work comprising an expansible tubular dowel element adapted to be inserted into alined bores in said pieces of work, an expander shorter than and insertable into said element and adapted to be operated from the exterior of said element to expand the latter for the aforesaid purpose, and also to release said element to enable the withdrawal of said expander and said element, and a spring located at one end of said element to interpose one of said work pieces and said expander to impart endwise movement thereto while disposed in said element to cause one end of said expander to project from said element to be grasped when the expander is in the releasing position, for the purpose of withdrawing said expander from said element.

3. The combination of an expansible tubular dowel element of spring metal having a single longitudinal slot, and an expander turnable within said dowel element in contact therewith, said expander having a longitudinal contact edge movable into and out of said slot by turning said expander, to expand said element or to allow said element to contract.

4. The combination of an expansible tubular dowel element having a longitudinal slot, and an expander turnable within said dowel element in contact therewith, said expander having a longitudinal contact edge movable into and out of said slot by turning said expander, to expand said element or to allow said element to contract, said expander being shorter than said element, and means located at one end of said element to interpose said expander and a piece of work, to impart endwise movement to said expander, to cause the outer end of the expander to project from said element, when the expander is in the releasing position, enabling said outer end to be gripped, for the purpose of withdrawing said expander from said element.

FREDERICK THOMAS BOWLER.
